UNITED STATES PATENT OFFICE.

GEORGE D. KINSEY, OF BROOKLYN, NEW YORK, ASSIGNOR TO THE AUSTRALIAN KNITTING COMPANY, OF PATERSON, NEW JERSEY.

DESIGN FOR KNITTED FABRIC.

SPECIFICATION forming part of Design No. 19,057, dated April 23, 1889.

Application filed March 7, 1889. Serial No. 302,338. Term of patent 7 years.

To all whom it may concern:

Be it known that I, GEORGE D. KINSEY, of Brooklyn, in the county of Kings and State of New York, have invented and produced a new and original Design for Knitted Fabrics, of which the following is a specification.

The accompanying drawing illustrates a design embodying my invention, the design being shown in the white portions of the figure.

A designates two approximately-parallel lines, which constitute the side edges of the

design. Intermediate of the lines A are diagonally-extending lines a a'. The lines a are straight, while the intermediate lines, a', are zigzagged at about midway in their lengths. 15

What I claim as my design is—

The design for knitted fabrics, substantially as herein shown and set forth.

GEORGE D. KINSEY.
